CHRISTIAN WILLIAM MANZ, OF BUFFALO, NEW YORK

MANHOLE PROTECTOR

Application filed May 13, 1932. Serial No. 611,202.

The invention relates to manholes, and particularly to protective means for uncovered manholes.

Manholes such as those in streets and roadways, normally include cast metal frames disposed at the street level, and provided with inner annular recesses for receiving removable covers. In order to obviate an obstruction in the street or roadway, the frames and manhole covers are made flush with the ground level. When the cover is removed and a workman has entered the manhole, surface water on the street can drain into the manhole upon the workman. This condition is particularly annoying in wet weather, although when the manhole is disposed adjacent a curb, it may exist for a long time after rain or snow has ceased falling. Further, when the cover of a manhole in a street or roadway is removed, it is necessary to erect a railing, or like obstruction, to prevent vehicles and persons from moving over the opening.

The present invention comprehends a protective device adapted to be fitted with the manhole frame when the cover is removed, to prevent water from draining into the manhole, and, at the same time, to present an obstruction to warn traffic of the uncovered manhole and prevent it from passing thereover.

These and other objects and advantages will become apparent from the following description of the typical embodiments of the invention illustrated in the accompanying drawing, wherein:

Fig. 1 is a perspective view disclosing the protective device installed in an uncovered manhole;

Fig. 2 is a vertical sectional view, likewise disclosing the device installed;

Fig. 3 is an enlarged fragmentary vertical section through the protective device per se;

Fig. 4 is a fragmentary plan view of the protective device;

Fig. 5 is a fragmentary vertical section taken along line 5-5 of Fig. 4; and

Fig. 6 is a fragmentary plan view of a modified construction.

As shown in Figs. 1 and 2, the manhole,

which may be disposed adjacent a curb 10, is delineated by a frame casting 11, having its upper surface 12, flush with the level of the street or roadway 13. According to conventional practice, the frame is illustrated as supported by beams 14 and having depending lugs 15 engaged between the beams. The upper inner periphery of the frame is recessed at 16 to provide a seat for a manhole cover (not illustrated) which normally closes the opening in the frame. The wall 20 of the recess is usually inclined from the vertical to facilitate insertion and removal of the cover.

The present invention comprehends a ring which may be inserted in the recess 16 at times when the cover is removed, and may be removed when it is again desired to replace the cover. As illustrated the ring includes a strip of metal 17, bent to conform generally to the contour of the recess 16 and having its ends 18 and 19 provided with interfitting tongues and grooves 21 and 22. Secured by fasteners 23 to the lower inner wall of member 17 is a band 24 of angle iron. At the ends of the latter are flanges 25, 26 apertured to receive an adjusting member 27. The adjusting member may comprise a shank having nuts 28 threaded thereto. By turning the latter, the flanges 25, 26 may be moved apart to expand the members 23 and 24.

Extending about the member 17 is a continuous band 31 of rubber or similar flexible gasket material. The lower edge of the band is preferably tapered, as indicated at 32, to compensate for the inclination of wall 20 of the manhole frame, and terminates in an inwardly directed flange 33 which underlies the lower leg 34 of the angle iron 24.

The protective ring, by reason of the initial formation of members 17, 24 and 31 is normally of less diameter than the recess 16 so that it may be readily inserted therein. The means 27, 28 may be adjusted to expand the ring to compress the gasket ring 31 and thus form a watertight seal with the manhole frame. By reason of the interlocking tongues and grooves 21, 22, the gasket is supported and may be compressed about its en-

tire periphery. The protective ring may be of any suitable height, but preferably such that when in place it will extend above the street level a distance substantially equal to 5 or greater than the height of the curb 10.

As another or additional precaution against the leakage of water between the ring and the manhole frame, clamping devices 35 may be applied to compress the bottom 10 flange 34 of the gasket. These devices may comprise turnbuckles having upper headed portions 36, adapted to engage in slots 37 formed in the leg 33 of the angle member 24, and lower hook portions 38 adapted to 15 engage under the lower edge of the manhole frame 11. After the protective ring has been placed in the manhole frame, the clamping devices may be positioned and tightened to draw the ring closely against 20 the horizontal seat surface of the frame.

When it is desired to replace the manhole cover, the protective ring may be removed by releasing the expanding means 27, 28, allowing the ring to contract to its normal size, and by releasing and removing from engaged position the turnbuckles or clamping means 35, 36, 38.

In order to safeguard the workman from being pinched by closing or contracting 20 movement of the tongue and groove ends of the band 17, or by contact with the sharp edge presented by these ends, an inverted U-shaped guard member 39 may be fitted 35 thereover, and may be held in position by fasteners 41. The guard member preferably is secured to but one end of the band 17 and has a sliding fit with the other end, so that it will not interfere with contraction or expansion of the protective ring.

40 The device illustrated in Figs. 1, 2 and 4 is normally contracted to be of smaller diameter than the recess 16 in the manhole frame, and may be expanded by the means 27, 28 to tightly engage the vertical walls 45 of the recess. However, if desired, the ring may be normally expanded so as to be of greater diameter than the frame recess, and may be contracted to reduce its diameter to permit insertion into the recess. This form 50 of the invention is depicted in Fig. 6 wherein flanges 25', 26' are apertured to receive contracting means consisting of a bolt 45 and a nut 26. The latter may be adjusted to contract the protective ring to permit it to be 55 inserted into the manhole frame. After being inserted into the frame and the contracting means released, the ring will expand by its own resiliency to firmly engage the frame and present a watertight wall 60 about the manhole.

It will be understood that the devices described and illustrated herein are merely illustrative of the inventive principles involved, and that these principles may be 65 embodied in devices having other structural

characteristics and arrangements, all within the purview of this invention.

What is claimed is:

1. In combination with a manhole frame, a removable member extending upwardly from said frame and defining an unbroken wall around the manhole to prevent entrance of surface fluids, and means for releasably securing said wall member with respect to said frame. 70
2. In combination with a manhole frame, a member extending upwardly from said frame, said member comprising a removable ring extending upwardly about the manhole and providing a dam therearound for preventing surface fluids from entering the manhole. 80
3. In combination with a manhole frame having an opening with substantially upright walls, a member inserted within said opening and extending upwardly beyond the upper edge of said frame, said member constituting a continuous and unbroken wall about the opening for preventing surface fluids from entering the manhole through the opening in the frame. 85
4. In combination with a manhole frame having an opening with substantially upright walls, an expansible member inserted within said opening and extending upwardly beyond the upper surface of the frame, said member being continuous and presenting an unbroken wall about the opening. 95
5. A manhole protective device comprising a ring adapted to seat upon a manhole frame and to extend upwardly above the upper surface thereof, said ring, including gasket means and means for pressing the gasket means into watertight contact with the manhole frame, said ring and gasket means constituting a dam to prevent surface fluids from entering the manhole. 100
6. In combination with a manhole frame, a protective ring adapted to seat upon said frame about the opening therein, said ring having a gasket portion at the lower surface thereof for contact with the frame, and said ring and gasket portion constituting a dam to prevent surface fluids from entering the manhole. 110
7. In combination with a manhole frame, a protective ring adapted to seat upon said frame about the opening therein, said ring having a gasket portion at the lower surface thereof for contact with the frame, and means for drawing said ring downwardly for compressing said gasket portion against the frame. 120
8. A protective ring for disposition upon a manhole frame to provide a wall about the opening in such frame, said ring having a ring-like gasket portion at the lower surface thereof for contact with the frame, and means engaged with the ring and engageable with the frame for drawing said ring to 125
- 130

ward the frame to thereby compress said gasket portion.

9. A protective ring for disposition upon a manhole frame to provide a wall about the opening in such frame; said ring comprising a member of angle cross-section having an inwardly directed lower flange and an upwardly directed flange, means adjacent the ends of the members for varying the diameter of the ring, a band of greater height than said upwardly directed flange secured thereabout and having interfitted tongued and grooved ends; adjustable means engaged with said inwardly directed flange and engageable with the manhole frame for drawing the ring toward the frame; a continuous flexible gasket extending about said band and having an annular portion underlying said inwardly directed flange, and an inverted U-shaped member engaged over said band above the tongued and grooved ends thereof.

10. A protective ring for insertion in the opening of a manhole frame, said ring comprising a band having the end portions thereof provided with interfitting tongues and grooves, a flexible gasket extending continuously about said band, and means for varying the diameter of said band.

11. A protective ring for insertion in the opening of a manhole frame; said ring comprising a band having the end portions thereof provided with interfitting tongues and grooves, and a flexible gasket extending continuously about said band.

12. A protective ring for insertion in the opening of a manhole frame for preventing the entrance of surface fluids into the manhole, said ring comprising a continuous flexible gasket, and means within said gasket for expanding it against the walls of the manhole opening, said gasket when in place extending above the upper surface of said frame.
